UNITED STATES PATENT OFFICE.

FREDERICK K. VIAL, OF CHICAGO, ILLINOIS, ASSIGNOR, BY MESNE ASSIGNMENTS, TO GRIFFIN WHEEL COMPANY, OF BOSTON, MASSACHUSETTS, A CORPORATION OF MASSACHUSETTS.

GRINDER.

1,171,812.

Specification of Letters Patent. Patented Feb. 15, 1916.

Application filed November 29, 1911. Serial No. 662,984.

To all whom it may concern:

Be it known that I, FREDERICK K. VIAL, a citizen of the United States, residing at Chicago, in the county of Cook and State of Illinois, have invented certain new and useful Improvements in Grinders, of which the following is a specification.

The principal object of my invention is to provide a new and improved device for 10 grinding car wheels.

Another object of my invention is to provide a grinding machine for truing up car wheels without removing them from their usual operative position in relation to the 15 car.

Still another object of my invention is to provide a machine to be installed in a pit under a railway track which may be employed to grind the wheels of a car standing 20 on the track over this pit.

Various further objects of my invention relate to the means by which the foregoing objects are accomplished and will be readily understood in connection with the following 25 specification and drawings, taken with the appended claims.

For the purpose of fully explaining the principle of my invention, I have illustrated one specific embodiment thereof, together 30 with a few detail modifications, in the accompanying drawings, and I now proceed to describe this particular one of the various forms in which my invention may be embodied.

Referring to these drawings—Figure 1 is a general side elevation of my improved apparatus showing one end of a car in operative relation thereto. Fig. 2 is a general plan view of the apparatus as it is installed 35 in the pit under the rails. Fig. 3 is an end elevation of the apparatus as viewed from the left in Figs. 1 and 2. Unlike Figs. 1 and 2, Fig. 3 shows the rails spread apart so as to permit the grinding wheels to engage the 40 car wheels. Fig. 4 is an elevation looking in the opposite direction from that of Fig. 3 and taken approximately on the line 4, 4 in Fig. 6, looking in the direction of the arrows. Fig. 5 is a top plan view of that part of the 45 apparatus adjacent to the grinding wheels, the rails being spread apart as already mentioned for Fig. 3. Fig. 6 is a side elevation of that part of the apparatus adjacent to the grinding wheels. Fig. 7 is a top plan 50 view on an enlarged scale of certain hydraulic

apparatus shown somewhat less in detail in Fig. 5. Fig. 7^a is a diagram of positions for certain valves of Fig. 7, open circles indicating open condition, and solid black circles indicating closure, of the corresponding valves at the corresponding positions. Fig. 8 is a side elevation of the apparatus shown in Fig. 7. Fig. 9 is a section of the lifting-jack taken on the line 9, 9 in Fig. 8, looking in the direction of the arrows. Fig. 10 is another section of the lifting-jack, taken at right angles to that of Fig. 9, that is, taken on the line 10, 10 of Fig. 9, looking in the direction of the arrows. Fig. 11 is a detail elevation, partly in section, of the hydraulic mechanism for spreading the rails. Fig. 12 is a similar elevation of the same apparatus, showing the parts in a different relative position. Fig. 13 is a longitudinal section of the series of valve chambers shown in top plan view in Fig. 7. Fig. 13 also shows the cam shaft and cams to actuate the corresponding valves. Fig. 13^a is a detail elevation of a ratchet and pawl also shown in Fig. 13. Figs. 14, 15, 16, 17, 18 and 19 are sections, 80 respectively, on the correspondingly numbered lines in Fig. 13, looking in the directions of the respective arrows. These views show the cams in corresponding simultaneous positions. Fig. 20 is an enlarged 85 vertical section of a hanger and valve casing, which are shown in their relation to associated mechanism in Figs. 11 and 12. Fig. 21 is a section corresponding to Fig. 20, but with the parts shown in a different relative position. Fig. 22 is a section of a pivotal hydraulic joint of which several are employed in the apparatus. Fig. 23 is a section of a detail of the mechanism that cooperates with the cams of Fig. 13. Fig. 24 is a section 90 of the apparatus adjacent to the grinding wheel shaft, this section being taken along the axis of said shaft. Figs. 24^a and 24^b are detail views of the grinding wheel guard. Fig. 25 is an axial section of a clutch of 100 which two are employed in the apparatus. Fig. 26 is an elevation of the same clutch, as viewed from the left in Fig. 25. Fig. 27 is a cross section on the line 27, 27 of Fig. 25, looking in the direction of the arrows. Fig. 28 is a sectional elevation, taken across the track rails, showing a modified embodiment of my invention adapted for use with car wheels not capable of being driven by their own electric motors. Fig. 29 is a cross sec- 110

tion on the line 29, 29 looking in the direction of the arrows.

On the floor 35 of the pit stand a series of columns 36 supporting the track rails 37. Sections 38 of these rails side by side are pivotally mounted at corresponding ends of each on the vertical shafts 40 journaled in brackets 39 that project from respective columns 36'. Thus the rail sections 38 may be swung outwardly from their normal position shown in Fig. 1 to the position shown in Fig. 5. In normal position the ends of the rail sections 38 that are remote from the columns 36', rest on the columns 36".

15 The car standing on the rails is designated as 41. The bar 42 is pivoted midway between the rails 37 so that its beveled ends can be wedged under a pair of truck wheels as shown, and thus hold the car fixed in 20 position on the rails 37. A similar wheel locking bar 43 is provided on the other side of the rail sections 38 so that when the truck is shifted to grind the other pair of wheels it may be locked by means of this 25 other bar 43. The locking bar 43 is actuated by means of a lever 45 connected by a link 44.

An electric motor 46 stands on the floor 35 of the pit and is connected by a driving 30 belt 47 to the band wheel 48 on the countershaft 49. At its ends this countershaft 49 carries two wide pulleys 50 from which bands 51 extend for the purpose of driving the grinding wheels as will be described 35 presently. The countershaft 49 also carries a band wheel from which a band 52 extends to drive the blower 53. This blower 53 draws air through the pipe 54 from the neighborhood of the grinders, as will be 40 explained later, and discharges this air through the pipe 55. From the countershaft 49 another band 56 extends to one of the two pulleys 57 and 58 on the drive shaft of a hydraulic pressure pump 59. One of 45 the pulleys 57 and 58 is loose and the other tight on the shaft so that the pump 59 can be started and stopped by shifting the belt 56.

Two grinding wheels 61 are provided on 50 respective shafts 60 and adapted to operate on the two car wheels at the ends of a single car axle. Each shaft 60 carries a pulley 62 which receives a respective driving band 51 already mentioned. This shaft 60 is 55 mounted in a frame 63 and this frame 63 is mounted in vertical guides in the frame 64, as shown in Fig. 5. The frame 64 in turn is mounted in horizontal guides on a column 66' that stands up from the base 66. Thus 60 it will be seen that the wheel 61 can be displaced laterally by moving the two frames 64 and 63 laterally, and also vertically by moving the frame 63 vertically with respect to the frame 64. A counterweight 65 69 mounted upon the pivoted lever 68 and

connected to the vertically moving frame 63 by means of the link 67 serves to balance the weight of the frame 63.

The handles 71 may be used for producing the vertical displacement of the grinding wheels 61 and the handles 77 may be used for producing the lateral displacement thereof. Rotation of a handle 71 acts through the beveled gears 72 to rotate the shaft 65 with its feather 73. The bevel gear wheel 74 turns with the shaft 65, but can slide thereon by virtue of the feather 73. This bevel gear wheel 74 engages the bevel gear wheel 75 which rotates the screw 76 passing through a nut on the frame 63 and thus raises or lowers the frame 63 and with it the emery wheel 61. Turning the handle 77 transmits rotation through the bevel gears 78 to the cross shaft 79 which has screw-threaded engagement with the frame 85 64 and thus traverses it to the right or the left.

The two shafts 65 for the respective emery wheels 61 are in alinement and the clutch controlled by the handle 81 is provided to couple these shafts together or uncouple them as may be desired. Similarly the alining shafts 79 may be coupled together or disconnected as desired by means of the clutch controlled by the handle 80. I will now describe one of these two clutches having the handles 80 and 81, making particular reference to Figs. 25, 26 and 27. The abutting ends of the alining shafts 79 are shown at 147. One shaft 79 has a cup-shaped member 148 keyed thereon within which is a split elastic ring 149. Within this ring 149 is a collar 150 keyed to the other shaft 79. The collar 150 has a short shaft 151 rotatably mounted therein parallel to the shaft 79 but eccentric thereto. A crank arm is keyed on the shaft 151 and has a screw stud 152 in its end. This shaft 151 has its end shaped elliptically in cross section, as shown at 153 in Fig. 27, and the extremities of the elliptical section abut, respectively, against one end of the split elastic ring 149 and the block 154. This block 154 in turn abuts against the other end of the split elastic ring 149. The sliding coned sleeve 155 on the shaft 79 115 has a peripheral groove 156 engaged by the studs 157 on the forked lever which terminates in the handle 80. When the handle 80 is moved so as to force the cone 155 under the stud 152, this rotates the transversely 120 widened end 153 of the shaft 151, and thereby forces apart the ends of the split ring 149 causing it to frictionally engage the cup 148. In this way the two shafts 79, abutting at 147, are caused to rotate together as one shaft. When the handle 80 is withdrawn the shafts may be rotated independently of each other.

The emery wheel 61 is surrounded by a hood 70, shown in section in Fig. 24 but 130

removed from Fig. 4; this is connected by a telescope joint 82 to the air exhaust pipe 54. The ends of the telescope joint 82 have ball and socket connections 83 so that the 5 vertical and lateral displacement of the emery wheel 61 is fully accommodated for. The hood 70 is not only for an air inlet but is a guard in case of bursting of the emery wheel 61. The swinging guard 184 is pivot-
10 ed on the side of the hood 70, one end 187 serving as a counterweight. The other end 185 passes across the periphery of the wheel 61 and a side guard 186 is attached thereto. The roller 158 carried by the swinging guard 15 rests against the tread of the car wheel. The guard deflects the dust from the emery wheel 61 down into the hood 70.

The stationary horizontal guides 84 have the slide 85 mounted between them. The 20 notch 159 shown in Fig. 10 is to accommodate the shaft 65. The slide 85 carries the upstanding cylinder 86 in which is the plunger 87. Mounted across the upper end of the plunger 87 is a short length of I-beam 25 88 carrying saddles 89 at its ends. The shape of these saddles 89 adapts them to fit under the electric motor casing beneath the car axle for the purpose of raising the car axle and the wheels at the ends thereof from 30 the track. The saddles 89 may be adjusted along the I-beam 88 and locked in place by set screws.

The hydraulic pressure pipe 90 is connected to the cylinder 86 below the plunger 35 87. The hydraulic cylinder 86 and the saddles 89 supported thereby may be traversed parallel to the rails 37 by means of the screw 92 operated by the handle 93; in this way the saddles 89 may be brought directly 40 below the part of the motor casing that they should properly engage to lift the same. The hydraulic pipe 90 is continued away from the pressure cylinder 86 in a pair of jointed sections 91 shown in Fig. 7 which 45 accommodate the horizontal displacement of the cylinder 86.

The hydraulic cylinder 94 has one cylinder head prolonged as an arm 95, and this arm 95 is pivoted to one of the rail sections 50 38. Within the cylinder 94 is a piston 96, and its piston rod 97 is pivotally connected to the other rail section 38. The relative movement of the piston 96 and the cylinder 94 either spreads the rail sections 38 or 55 draws them together.

By means of a pair of lock nuts 99, a return rod 98 is attached to the end of the piston rod 97. Two hangers 143 are mounted on the cylinder 94, and both hangers 60 143 have alining holes 101 therethrough. The return rod 98 passes through the two holes 101, and its end carries a dog 100, which actuates certain valves, as will be described later.

65 The hydraulic pressure pump 59 has an

outgoing pressure pipe 102 that leads by three branches 102' to the multiple valve box 103. This valve box extends parallel with a shaft 104 that carries a pointer 105—see Fig. 3—at its end. The extremity of 70 the shaft 104 is squared to receive a crank handle, as shown in Figs. 3 and 6. The ratchet 182 and coacting pawl 183 permit rotation of shaft 104 only in a clockwise direction as viewed in Fig. 3. The shaft 75 104 extends under the valve box 103 and carries six cams—106, 107, 108, 109, 110 and 111. Within the valve box, above these respective cams, are six valves, 112, 113, 114, 115, 116 and 117. These valves are kept 80 normally closed by respective springs above them, but are adapted to be opened by their corresponding cams, as shown in Figs. 13 to 19 inclusive. Over each cam is a vertically reciprocating block 144, with an adjustable screw plug 145 therein, and each stem 146 that raises its respective valve may be adjusted in height by screwing or unscrewing this plug 145.

The three branches 102' of the pressure 90 supply pipe 102 lead, respectively, to the valves 112, 113 and 114. From the valve 112 there extends a pipe 119 with a check valve 118 therein. This pipe 119 is connected through the flexible coupling 91 to the lifting jack 86—87. A branch 121 leads through the valve 117 and branch pipe 120' to the oil return pipe 120 and thence back to the hydraulic jack 59. A pipe 122 extends from the valve 113 and is connected to the flexible 100 coupling 123. This flexible connection 123 is attached by a joint 124 (shown in section in Fig. 22) and the pipe 125 to a chamber in one hanger casing 143'. From this chamber in the casing 143' a pipe 126 connects, 105 through a port 127, to the interior of the hydraulic pressure cylinder 94 behind the piston 96. Branch pipe 128 leads from flexible connection 123 through valve 116 and pipes 120', 120 back to the pump 59. 110

The pipe 129 leads from the valve 114 to the flexible pipe 130. Through this flexible connection 130, joint 131, and pipe 132, there is a conduit into the chamber within the casing 143' supported by the hanger 143. 115 This chamber is closed above by a valve 133, normally held to its seat by the spring 134. The plunger 135 is adapted to depress the valve 133 when its upper end is engaged by the dog 100 on the return rod 98. The 120 pipe 136 extends from the casing 143' below the valve 133 to the port 137, opening into the cylinder 94 in front of the piston 96. Branch pipe 142 leads from the flexible connection 130 through valve 115, branch 125 120' and pipe 120, back to pump 59.

The two hangers 143, with their valve casings 143', are substantially alike, and part of the details are shown on one of them and part on the other, as viewed in 130

Figs. 11 and 12. The enlarged views of Figs. 20 and 21 show the left-hand hanger 143 and casing 143', as viewed in Figs. 11 and 12.

5 In Fig. 11 the right-hand hanger and casing are shown partly in section, with the valve removed, so as to clearly show the connection of the pipe 126 behind the casing 143'. The pipe 136 connects in a similar 10 manner to the front of the left-hand casing 143', as viewed in Figs. 11 and 12. The spaces in the two casings 143', above the respective valves 133, are connected together by pipes 138, which have an intermediate 15 depending branch pipe 139 connected by the joint 140 and the flexible connection 141 to the return pipe 120.

An electric conductor 179 extends from the regular trolley wire 177 to the fixed 20 plate of a water rheostat 175, and a return conductor 180 goes back from the movable plate of the water rheostat 175 to the auxiliary trolley wire 178. The rheostat is adjusted by the screw shaft 176 which may be 25 rotated by a crank applied to its squared end.

The man who attends to the operation of the apparatus stands on the floor 35 of the pit, in front of the handles 71, 77 and 93. 30 A car 41 is run along the rails 37 until one pair of truck wheels stands on the movable track sections 38. The operator, by means of the lever 45, turns the locking device 42 so as to wedge its ends under a pair of 35 wheels on respectively opposite sides thereof; this holds the car 41 in position on the track rails 37.

By means of crank handle 93 the saddles 89 are brought under the car axle and if necessary 40 the saddles 89 are adjusted along the I-beam 88. The operator then applies a removable crank to the shaft 104, and rotates it so that the pointer 105 will go from position "4" to position "1." This brings 45 all the cams 106 to 111 to the position shown in Figs. 13 to 19. An inspection of these cams will show that in this position "1" only valve 112 of the six valves 112 to 117 will be open. Accordingly, assuming the pump 50 55 to be in operation, oil will then flow therefrom under pressure through the conduit 102-112-118-119-91-90 into the cylinder 86, under the plunger 87, thus elevating the saddles or yokes 89 and with them the 55 axle of the truck resting thereon. This will raise the pair of truck wheels from the rail sections 38. It should be remembered that Figs. 14 to 19 are taken looking in the opposite direction from Fig. 3, and therefore the 60 clockwise rotation of shaft 104 in Fig. 3 gives counter clockwise rotation in Figs. 14 to 19, as indicated by arrow 174 in Fig. 14. Next, the operator gives the shaft 104 a further turn of 90°, bringing the index hand 65 105 to position "2." As will be seen by in-

specting Figs. 14 to 19, this closes valve 112 and opens valves 113 and 115. The closing of valve 112 stops the flow of oil to the jack 86-87, and thereby stops the further elevation of the car wheels. The opening of the valve 113 permits oil under pressure to flow through the conduit traced as follows: 59-102-113-122-123-124-125-126-127. Thus, the oil entering the port 127 pushes the piston 96 and the cylinder head behind the 75 same apart from each other and spreads the rail sections 38. The opening of the valve 115 permits the oil within the cylinder 94 in front of the piston 96 to exhaust through the conduit traced as follows: 137-136-132-80 131-130-142-115-120-59. When the dog 100 reaches the position shown in Fig. 12, it opens the valve in the right hand casing 143', as viewed in Fig. 12, and permits the pressure oil entering the casing 143' from the pipe 125 to leave through the pipe 138, instead of through the pipe 126. Thus, relative motion of the piston 96 and cylinder 94 is arrested, and the further stream of oil from the pump 59 goes through the 90 pipes 125 and 138, and thence through the conduit as follows: 138-139-140-141-120. Having raised the wheels and spread the rail sections 38 from under them, the operator is next ready to start the motor of the 95 electric car, and thus rotate the wheels that are to be ground. In doing this he regulates the speed by means of the water rheostat 175 controlled by a detachable crank engaging the squared end of the screw shaft 176. 100 Previously to this the brushes of the motors for other wheels than those being ground have been raised, and the trolley wheel 181 of the car shifted to the auxiliary trolley wire 178. By means of a crank 77, the 105 emery wheels 61 are traversed to about the center of the treads of the car wheels to be ground. After this, by means of the crank 71, the emery wheels are raised until they engage the car wheel treads and commence 110 grinding them. If the clutches 80 and 81 are kept in engagement, then both the emery wheels 61 may be adjusted alike and simultaneously by the rotation of either one of the handles 71, or either one of the handles 77. If for any reason it becomes desirable 115 to adjust either emery wheel 61 independently of the other, either one or both of the clutches 80 and 81 may be disconnected to permit this. During the grinding of the car 120 wheels the emery wheels 61 may be traversed across the car wheel treads, as seems desirable, by operating either or both of the crank handles 77, and as the car wheels become ground away the emery wheels 61 can 125 be fed to their work by operating either or both of the crank handles 71. After the wheels of the car 41 have been properly ground in the manner described, the grinding wheels 61 are lowered by means of one 130

or both of the cranks 71. Then the shaft 104 is given another quarter turn so as to bring the index hand 105 to position "3." This rotates the cams illustrated in Figs. 13 to 19 correspondingly and closes valves 113 and 115 and opens valves 114 and 116. Accordingly the oil flows under pressure from the oil pump 59 through the conduit traced as follows: 102—102—114—129—130—131—132—136—137. This oil under pressure entering the cylinder 94 through the port 137 pushes the piston 96 and the cylinder 94 together and thus the rail sections 38 are drawn back to their normal position. The movement of the piston 96 causes the oil contained therein to discharge back to the hydraulic pump 59 through the conduit traced as follows: 127—126—125—124—123—128—116—120'—120. This return movement of the piston 96 relatively to the cylinder 94 continues until the dog 100 strikes the plunger 135 and thereby depresses the valve 133. When this happens the inflowing oil under pressure enters the casing 143' by the pipe 132, but instead of leaving by the pipe 136, it leaves by the pipe 138 and returns to the hydraulic pump 59 through the conduit traced as follows: 138—139—140—141—120. Having returned the rail sections 38 to their normal position, another quarter turn of the shaft 104 brings the index thereon to the position "4." This closes the valves 114 and 116 and opens the valve 117 permitting the oil to discharge from the lifting jack cylinder 86 back to the hydraulic pump 59 through the conduit traced as follows: 90—91—121—117—120—120. Accordingly the car wheels that have been ground settle down on the rail sections 38 and then the car may be moved so as to bring the other pair of truck wheels over the grinding wheels 61. In this case the car is locked on the rails by the bar 43.

The modification shown in Figs. 28 and 29 illustrates the application of my invention for the purpose of grinding car wheels mounted on an axle not equipped with an electric motor. In this case I provide two hydraulic jack cylinders 160 with their respective plunger pistons 161. Two heavy split rings 162 are provided which may be locked around the car axle by a relative longitudinal displacement, the joints being indicated at 163. Each ring 162 has four inclined keyways 164 and respective keys or wedges 165 are provided to go in these keyways 164. Screws with hand wheels 166 are provided to crowd the wedges 165 in place. The axles of ordinary freight cars are in many instances not turned or trued up and therefore the apparatus just described is provided in order to accurately center the rings 162. To assist in centering these rings 162^a, gage 167 (indicated in dotted lines) is provided. Such car wheel axles as have just

been mentioned generally have flanges 173 and the axle is turned up to these flanges. The wheels do not go on the axles quite to these flanges and thus there is a space 172 between the wheels and the flanges 173 which may be engaged by the ends of the gage 167. A split sprocket wheel 168 is provided which may be clamped around the middle part of the axle after removing the gage 167. This is driven by a chain from the sprocket wheel 169 on the counter-shaft 170. The lifting jack plungers 161 carry bearing cups 171 at their upper ends adapted to fit the rings 162. After the rings 162 are applied and centered, as described, the split sprocket 168 is applied and then the jacks 161 are operated. Thus the wheel axle rests in the cups 171 as bearings and may be rotated from the counter-shaft 170. The rest of the operations of grinding may be similar to those described for that embodiment of my invention relating to driving the wheels by the electric motor of the car. It will be perceived that as the jacks raise the axle shaft in Fig. 28 the sprocket wheel 168 recedes from the sprocket wheel 169. The chain on these sprocket wheels is provided with sufficient slack and an adjustable tightener takes up this slack.

It will be seen that the apparatus herein described is adapted to quickly and conveniently grind the wheels of an ordinary railway car. The operation can be performed in the car barn or shop during a few hours when the car happens to be out of service.

I claim:

1. In combination, a track, grinding wheels located beneath each rail of said track, means to support a pair of car wheels connected by an axle to permit displacement of said track, means to displace opposite rails of said track angularly in horizontal planes, and means to move said grinding wheels in vertical planes to contact with said car wheels.

2. In a device of the class described, a track having means adjacent thereto for grinding the wheels of a car truck standing on said track, and a bar pivoted midway between the rails of the track, the ends of said bar being adapted to go under opposite sides of a pair of wheels of the truck so as to hold the truck while grinding is taking place.

3. In a device of the class described a track having a pit thereunder, the rails of said track having displaceable sections, mechanism to grind said wheels, and two bars, each pivoted at a point between the rails and on respective sides of the displaceable sections so that when one pair of wheels of a car truck is on the displaceable sections one of these bars may be rotated to bring the ends thereof under the respective wheels of the other pair of wheels of the same truck.

so as to hold the truck in position on the track.

4. In a device of the class described, a track, a pair of grinding wheels adapted for use in grinding a pair of car wheels of a car truck standing on said track, means to support said pair of wheels to be ground, and means to lock another pair of car wheels of said truck in position on said track to hold said truck in position while said first mentioned pair of car wheels are being ground.

5. In a device of the class described, a track having displaceable sections, means to support a pair of truck wheels over said sections and thereby permit displacement of the sections, means to displace said sections, a pair of grinding wheels under the respective car wheels, power-driving connections therefor, and means to displace said grinding wheels both vertically and laterally independently of the movement of said displaceable sections so as to bring them in engagement with the respective car wheels at any desired point across the tread surfaces thereof.

6. In a device of the class described, a track pit car wheel grinding machine having two grinding wheels adapted to simultaneously engage two car wheels on the same axle, two crank handles with respective transmitting mechanisms therefrom to raise and lower the said grinding wheels, and a clutch adapted to connect said respective mechanisms together so that they may be operated simultaneously by one of said crank handles.

7. In a device of the class described, a track pit car wheel grinding machine having two grinding wheels adapted to simultaneously engage two car wheels on the same axle, two crank handles with respective transmitting mechanisms therefrom to laterally traverse the said grinding wheels, and a clutch adapted to connect said respective mechanisms together so that they may be operated simultaneously by one of said crank handles.

8. In a device of the class described a track pit grinding apparatus for grinding car wheels, grinding wheels under the respective car wheels adapted to be raised and brought into engagement with said car wheels, a lever pivoted at an intermediate point associated with each grinding wheel, carriages sliding in vertical guides carrying the respective grinding wheels, a counterweight on one end of each lever, and a link connecting the other end of each lever to the respective grinding wheel carriage.

9. In a device of the class described, a grinding wheel adapted to be located beneath a track for use in grinding car wheels, means for adjusting said grinding wheel laterally and vertically to contact with said

car wheel, a hood surrounding said grinding wheel and supported to move therewith, and an exhaust air conduit leading from said hood, said conduit having telescoping sections and a ball and socket joint at its end to permit said movements of said grinding wheel and hood.

10. In a device of the class described, a grinding wheel adapted to engage a car wheel on the tread surface thereof, a hood around said wheel, a guard pivoted on said hood, and a roller on the guard adapted to engage the tread surface of the car wheel.

11. In a device of the class described, a track having a pit thereunder, a jack in said pit to raise a pair of wheels from said track, means to lock another pair of wheels of the same truck, means to shift the jack along the direction of the track so as to bring it directly under the axle of the wheels to be lifted, and grinding mechanism to act upon such wheels.

12. In combination, a track, grinding wheels located beneath each rail of said track, means to displace the rail sections above said grinding wheels, means to support a pair of car wheels connected by an axle to permit said displacement, means to move said supporting means longitudinally of said track to a position adjacent said wheels to be supported, and means to move said grinding wheels into engagement with said car wheels.

13. In a device of the class described, a track, car wheel grinding wheels located beneath the respective rails of said track, a single adjusting means for moving both of said grinding wheels simultaneously in a vertical direction, and a single adjusting means for moving both of said grinding wheels simultaneously in a lateral direction.

14. In a device of the class described, a track, car wheel grinding wheels located beneath the respective rails of said track, and a single adjusting means for moving both of said grinding wheels simultaneously in a vertical direction, said adjusting means also being arranged to permit movement of said grinding wheels independently of each other.

15. In a device of the class described, a track, car wheel grinding wheels located beneath the respective rails of said track, and a single adjusting means for moving both of said grinding wheels simultaneously in a lateral direction, said adjusting means being also arranged to permit movement of said grinding wheels independently of each other.

16. In a device of the class described, a track having displaceable sections, means to support a pair of truck wheels over said sections and thereby permit displacement of said sections, means to displace said sections, a pair of grinding wheels under the respec-

tive car wheels, means for driving said grinding wheels, and means to displace said grinding wheels both laterally and vertically to bring them into engagement with the respective car wheels at any desired points on the tread surfaces thereof.

17. In a device of the class described, a car wheel grinding machine having two grinding wheels adapted to engage simultaneously two car wheels on the same axle, two adjusting mechanisms for raising and lowering said grinding wheels independently of each other, and operating means for driving each of said adjusting mechanisms, and means for connecting said adjusting mechanisms together so that they may be operated simultaneously by one of said operating means.

18. In a device of the class described, a car wheel grinding machine having two grinding wheels adapted to engage simultaneously two car wheels on the same axle, two adjusting mechanisms for moving said

grinding wheels laterally across the car wheels being ground, an operating means for driving each of said adjusting mechanisms, and means for connecting said adjusting mechanisms so that they may be operated simultaneously by one of said operating means.

19. In a machine for grinding car wheels, a supporting member, a frame slidably mounted in said supporting member, a grinding wheel carried by said frame, means for adjusting said frame and grinding wheel with respect to said support, and a counter weight operatively connected to said frame and said support to counter-balance the weight of said frame and parts carried thereby.

In testimony whereof, I have subscribed my name.

FREDERICK K. VIAL.
